Primary Examiner—Sandra L. Morris[57] **CLAIM**

The ornamental design for a deck of cards, as shown and described.

DESCRIPTION

FIG. 1 is the front of the eighth note card, showing one card in the deck of cards, showing my new design;
FIG. 2 is the front of the whole note card;
FIG. 3 is the front of the half note card;
FIG. 4 is the front of the quarter note card;
FIG. 5 is the front of the quarter rest card;
FIG. 6 is the front of the half rest and whole rest card;
FIG. 7 is the front of the dot card;
FIG. 8 is the front of the eighth rest card;
FIG. 9 is the front of the $\frac{3}{4}$ meter card;
FIG. 10 is the front of the $\frac{1}{4}$ meter card;
FIG. 11 is the front of the $\frac{1}{2}$ meter card;
FIG. 12 is the front of the $\frac{3}{4}$ meter card;
FIG. 13 is the front of the wild card; and,
FIG. 14 is the back of all cards in the deck of cards, showing my new design.
The cards are of conventional thickness.
